Primary Examiner — Jennifer Rivard*Assistant Examiner* — April Rivas(57) CLAIM

The ornamental design for a jewelry bag, as shown and described.

DESCRIPTION

FIG. 1 is a front perspective view of a jewelry bag showing the claimed design;

FIG. 2 is another front perspective view thereof;

FIG. 3 is a front elevational view thereof;

FIG. 4 is a rear elevational view thereof;

FIG. 5 is a right side elevational thereof;

FIG. 6 is a left side elevational view thereof;

FIG. 7 is a top plan view thereof; and,

FIG. 8 is a bottom plan view thereof.

The broken lines in the figures show portions of the jewelry bag that form no part of the claimed design.
